US0D1024668S

(12) **United States Design Patent** (10) Patent No.: **US D1,024,668 S**
(45) Date of Patent: ** Apr. 30, 2024

(54) **JAR LID**

(71) Applicant: **Everich And Tomic Housewares Co., Ltd**, ZheJiang (CN)

(72) Inventor: **Huajun Yao**, Hangzhou (CN)

(**) Term: **15 Years**

(21) Appl. No.: **29/848,322**

(22) Filed: **Aug. 1, 2022**

(30) **Foreign Application Priority Data**

Feb. 28, 2022 (CN) 202230098682.X

(51) LOC (14) Cl. **07-01**

(52) U.S. Cl.

USPC **D7/391**; D7/396.2; D9/435

(57) **CLAIM**

The ornamental design for a jar lid, as shown and described.

DESCRIPTION

FIG. 1 is a front and top perspective view of a jar lid, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the figures illustrate portions of the jar lid that form no part of the claimed design.

1 Claim, 8 Drawing Sheets
